UNITED STATES PATENT OFFICE.

EDWIN E. FARIS, OF CHATTANOOGA, TENNESSEE.

VALVE LIFTER.

1,417,370.

Specification of Letters Patent. Patented May 23, 1922.

Application filed February 3, 1920. Serial No. 356,058.

To all whom it may concern:

Be it known that I, EDWIN E. FARIS, a citizen of the United States, and a resident of the city of Chattanooga, county of Hamilton, and State of Tennessee, have invented an Improvement in Valve Lifters, of which the following is a specification.

This invention relates to improvements in tools for use in removing valves from internal combustion engines and more particularly to improvements in so-called valve lifters used to compress the usual valve spring prior to the removal of the valve.

It is an object of the invention to provide a tool of the class referred to which is simple in construction, economical of manufacture and efficient in operation.

A preferred embodiment of the invention has been selected herein for purposes of illustration and description without limiting the invention to the structure shown and described. In the accompanying drawings,

Figure 1 is a side elevation of a preferred embodiment of the invention showing the tool in position for operation.

Figure 2 is a top plan view of the tool shown in Figure 1.

Figure 3 is an end view of the tool shown in Figure 1, and

Figure 4 illustrates the operation of the tool.

Referring to the drawings it will be seen that the tool comprises a U-shaped member 1 having a seat 2 formed at the extremity 35 of the lower projection of the U; the said seat being so formed that it will engage the usual spring holding washer which is a part of the usual construction of valves of the type with which the tool is intended to be 40 used. As shown in the drawings this seat 2 is provided with an opening 3 and an in-turned ledge 4 together with a semi-circular back plate 5 having a curvature approximating that of the usual coiled valve 45 spring. The seat 2 may be attached to the lower arm of the U-shaped member or formed integrally therewith as shown in the drawings.

The upper arm of the U-shaped member 50 is shorter than the lower arm and at its end is pivoted a lever 6; the pivot being formed in any suitable manner as by a stud bolt 7. The lever 6 projects beyond the closed end of the U where it is bent downwardly 55 and formed into a handle 8. The other end of the lever 6 is provided with means to

engage a part of the engine, preferably the head of the valve which is to be removed; the said means being shown as a threaded bolt 9 having its lower end 10 pointed and 60 its upper end formed with a cross-piece 11. This bolt is threaded in the enlarged end 12 of the lever 6.

In suitable position on the U-shaped frame, herein appearing as a projection of 65 the upper arm of the frame, is formed a handle 13 to co-operate with the handle 8. It will appear from Figure 2 that the end 12 of the lever 6 is offset from the vertical plane of the lever so as to bring the point 70 of the screw 10 directly above the center of the seat 2.

In order that the operation of the tool may be clearly understood a fragmentary section through the valve of an internal 75 combustion engine is shown in dotted lines in Figures 1 and 4. A valve 14 having a head 15 and stem 16 is shown mounted in a valve guide 17 and held upon its seat 18 by a valve spring 19 resting upon a valve 80 spring washer 20 which in turn is held in position by a pin 21 passing through a hole in the lower end of the valve stem. These parts are shown merely to illustrate a common type of valve construction and the tool 85 may of course be used to advantage with other and differently constructed valves.

In removing or replacing valves in internal combustion engines, particularly automobile engines, it is highly desirable to 90 have a simple easily operated tool for compressing the valve spring to enable the mechanic to quickly remove or replace the fastening means such as the pin 21 which holds the valve spring in position. With certain 95 of the tools heretofore provided for this purpose and operating to compress the spring against some extraneous part of the engine, the valve stem is easily raised with the valve spring and therefore does not expose the fastening pin 21 so that it may be withdrawn. Furthermore, some tools require the removal of exhaust and inlet manifolds and other connections before they can be placed in position for operation. Some 105 tools heretofore provided require both hands of a mechanic either for placing in position or compressing the spring and are also very apt to slip and let the spring fly back before the fastening means has been removed 110 or replaced as the case may be.

The tool hereinabove described overcomes

the objections above noted. The shoe 2 is so designed that it may be quickly brought into proper position and retained in engagement with the spring washer by the action of compressing the spring. It will be seen that the semi-circular rear wall of the seat 5 will bear against the spring washer and that the natural tendency to bear down on the handle 13 will hold this in close engagement with the washer. The tool is adapted to engage at its other end the valve head thus holding the valve against its seat during the compression of the spring. By turning the bolt 9 the tool may be adjusted for different valve stem lengths within certain limits. The handles 8 and 13 are so positioned that they may be grasped by one hand while the other hand is free to remove or replace the fastening pin 21. The relative positions of the handles 8 and 13 are such that when they are gripped to bring them together, downward pressure on the handle 13 will tend to hold the seat 2 in engagement with the valve spring, tending to force it to the right in Figures 1 and 2, while the upward pressure on the handle 8 acting through the fulcrum 7 raises the U-shaped frame and compresses the spring as shown in Figure 4.

It will be understood that the invention may be variously embodied and the preferred form shown herein variously modified within the scope of the subjoined claims.

I claim as my invention:

1. A tool for compressing valve springs comprising two pivoted members, one of said members being U-shaped and having the

other member pivoted thereto, means upon one member to engage a valve spring, means upon the other member to engage the valve, a handle formed on said U-shaped member, 40 and a handle formed at the adjacent end of the lever, the said handles being so positioned that the valve spring will be compressed by causing said handles to approach each other.

2. A tool for compressing valve springs comprising a U-shaped member adapted to engage a valve spring at one end, a lever pivoted at the other end of the U-shaped member and projecting beyond the bottom 50 of the U to form a handle, and a co-operating handle on the U-shaped member, whereby as said handles are drawn together the remote end of the lever and the extremity of one side of the U-shaped member are 55 brought together to compress the spring.

3. A tool for compressing valve springs comprising members pivoted together, one of said members being U-shaped and having at one end an offset portion of semicircular 60 contour for engaging the edge of a washer which engages a valve spring, and ledges forming a part of said portion for engaging the base of said washer, a second member carrying in one of its ends an adjustable pin 65 for engaging a valve, and means for relatively moving said members.

In testimony whereof, I have signed my name to this specification this 24 day of January, A. D. 1920.

EDWIN E. FARIS.
